UNITED STATES PATENT OFFICE

FRANK W. MILLER, OF CHICAGO, ILLINOIS

SMOKE ELIMINATOR

Application filed April 7, 1927. Serial No. 181,692.

This invention pertains generally to smoke eliminators of the type which promote complete combustion of fuel to thus eliminate smoke rather than the type which separate out from the products of combustion the unburned matter and dispose of it without burning it. While this invention may be applied to any fuel burning apparatus regardless of whether the fuel be normally gaseous, liquid or solid, it is herein illustrated as applied to a locomotive of the type now commonly in use.

One of the objects of this invention is to provide an apparatus for the elimination of smoke and which is capable of promoting the combustion of unburned matter in the products of combustion.

Another object of this invention is to provide an apparatus for eliminating smoke by promoting the complete combustion of matter in the products of combustion which otherwise would have remained unburned, this promoted combustion taking place within the fuel burning apparatus at a point where it produces useful heat.

Another object is to provide apparatus for eliminating smoke and adapted to deliver in regulatable quantities air for the promotion of combustion of unburned matter in the products of combustion, the delivery of the air into the products taking place without chilling the burning fuel.

Another object is to introduce air into the products of combustion to promote the combustion of unburned matter therein without adversely affecting the normal draft in the fuel burning apparatus.

Another object is to provide apparatus for smoke elimination having means for accurately regulating the amount of air introduced for smoke elimination purposes in proportion to the quantity of unburned matter existing simultaneously in the products of combustion.

Another object of this invention is to provide a smoke elimination apparatus particularly adaptable to use on locomotives and capable of effecting smoke elimination when the locomotive is standing in the terminal or when it is moving on the rails.

Another object of this invention is to introduce the air for smoke elimination at a point in the fuel burning apparatus where the air and products of combustion during their mixing will be heated by radiated or reflected heat or both.

Another object is to provide smoke elimination apparatus having any or all of the above advantages as well as other advantages, easily operated and installed and capable of being manufactured, installed and operated at an extremely low cost.

Other inherent objects, advantages and capabilities will later become apparent.

Referring now to the drawings in which the invention is illustrated as applied to locomotives,

Fig. 1 is a vertical central longitudinal section of a locomotive fire box showing the air spray heads on one side of the box in position, with a portion of the boiler in elevation showing the manually operated air valve.

Fig. 2 is a horizontal section taken on the line 2—2 of Fig. 1.

Fig. 3 is an elevation showing a locomotive equipped with the smoke eliminator, showing two sources of high pressure air supply.

Fig. 4 is a vertical central longitudinal section of a jet and spray head.

Fig. 5 is a plan view of the device shown in Fig. 4.

Referring now in greater detail to the drawings, a locomotive fire box 1 is illustrated as having a bed of burning fuel 2, such as coal. The usual fire box doorway 3 is provided for feeding of the fire.

At a certain distance above the normal level of the fire bed, two rows of spray heads 4, one row on each side of the fire box are positioned. Special spray heads 5 are located as illustrated for a purpose hereinafter explained. Leading into each of the spray heads is a tube 6 which supports its respective spray head and is fixed in some suitable manner in the walls of the fire box. The outer end of each tube flares outwardly as at 7 so that high pressure air coming through the pipes 8 and discharging from the jets 9 will entrain along with it quantities of

air at atmospheric pressure proportionate to the amount of high pressure air being discharged. Each spray head is provided with a discharge opening 11 which is formed in the shape of a narrow slot extending horizontally for such a distance as to enable the spray head to discharge a thin sheet of air at high velocity. Other types of spray heads may be used so long as the desired result is obtained, namely the projection of sufficient quantities of air into the products of combustion to supply the additional air required for smoke elimination. The spray heads 5 are designed somewhat differently from the other spray heads in order that they may discharge streams of air into the front of the fire box to properly mix with any of the products of combustion which may arise in that space.

Not only are the spray heads intended to completely cover all of the products of combustion arising from the fire bed to effect the thorough mixing of air with those products but it is important that the air thus sprayed not adversely affect the normal draft from the fire bed to the smoke stack. Consequently, it is desirable to direct the streams of air generally in the direction of the exhausting products of combustion. As the practice of firing may differ and as the draft conditions in locomotives may depend upon the design of the fire box and the boiler, it is very easy to position the spray heads to effect the desired efficient mixing of air and hot gases. The height of the spray heads will also vary with different locomotives and one thing that will always be avoided is a chilling of the bed of fire by the injected streams of air. Such chilling will easily be prevented by disposing the spray heads sufficiently above the fire bed; yet the spray heads will be as low as may be proper so that the air will mix with the gases in the zone where a large amount of heat is radiated from the fire bed or from the walls of the fire box. In some cases where this smoke eliminator is applied to other types of fuel burning apparatus, the zone in which the air and products of combustion mix may be receiving heat reflected from parts of the apparatus other than from the fire bed or it may be receiving heat from both the fire bed and the walls or parts of the apparatus.

While the drawings show the apparatus installed in a locomotive in which a solid fuel such as coal is being burned, it should be evident that this smoke eliminator will work as well with locomotives burning fuel which is normally liquid or normally gaseous and also with other fuel burning devices utilizing fuels of any kind. The positioning of the air injectors will, of course, then depend upon the nature of the fuel, the draft conditions and the type of the fuel burning device.

As a means for regulating the air which is to be sprayed into the fire box, there is provided a hand operated valve 12 having a handle 13 which may be rotated into any one of several positions and possibly spring locked in those positions. If desirable, the rotation of this handle into the various positions will cause different quantities of air to pass through the valve to thereafter be sprayed into the fire box. This type of valve may be found particularly useful in locomotive firing as the handle may be easily pushed into any one of several positions, and easily released therefrom thus giving the operator an easy means of injecting just enough air into the fire box to properly mix with the products of combustion to burn the amount of unburned matter existing in the products at the instant that the air is being injected. The amount of unburned matter will, of course, depend upon the condition of the bed of fire and the amount of fresh fuel being added. It appears then that when the fireman is throwing fresh coal upon his bed of fire, he can quickly and with a mere stroke of the hand cause just enough air to be injected into the fire box to unite with the hot gases therein to cause the combustion of whatever incompletely burned matter may be arising from the fire bed. Not only will solid particles of carbon be thus consumed, but certain noxious gases may also be eliminated as the air is sprayed into the fire box, for instance, carbon monoxide will be instantly converted into carbon dioxide.

The air regulated by the valve 12 when the locomotive is in the terminal may be taken from the terminal air storage tank 14 through the pipe 15 or it may be taken from the air tank 16 which is located on the locomotive itself. Consequently, though a fire is maintained in the locomotive while in the terminal, all smoke will be eliminated. Likewise, while the locomotive is moving on the rails in the vicinity of habitations where smoke is proscribed against, the fireman may use air from the locomotive air tank to entirely eliminate the smoke.

In order to obtain sufficient air for the complete combustion of the unburned particles existing in the products of combustion and to properly distribute the injected air wherever needed, it will not usually be necessary to obtain all of such air from the storage tanks where the air is maintained at pressure of perhaps ninety pounds. It is found that the desired results may be obtained by entraining along with the high pressure air a certain amount of air at atmospheric pressure, this being done by means of the jets 9 and the tubes 6, as shown in Figure 2. The proportion of high pressure air and air at atmospheric pressure will be varied in accordance with the conditions being coped with in a particular fuel burning apparatus.

Not only does this apparatus eliminate smoke but in its particular method of operation certain efficiencies peculiar to it arise therefrom which are of themselves of great advantage. By burning the unburned particles in the fire box particles of fuel which would otherwise have passed out in the products of combustion unburned, the deposits of soot in the fire tubes and elsewhere in the boiler between the fire box and the ultimate exit of the gases is entirely eliminated with resultant greater efficiency, and at the same time the completion of the combustion within the fire box produces useful heat which is created where it will do the most good.

Whenever the fuel is burning without producing any smoke, the valve may be moved to the closed position. If there should be any tendency for dust particles or soot to accumulate on the ports of the spray heads while the valve is closed, such deposits may be properly received upon the slightly outward flaring lips 17, shown in Fig. 4. Such deposits here will protect the edges of the ports from the heat radiated in the fire beds and yet will easily be blown therefrom as soon as air is again discharged from the spray heads. Should it be found necessary in order to keep the spray heads in good condition, it would very easily be possible to permit a slight amount of compressed air to by-pass around the valve or go through it and be discharged from each spray head in small quantities sufficient to keep the heads cool, but not in quantities large enough to cool the interior of the fire box.

It should be understood that various modifications are comprehended by this invention and may be made without departing from its spirit and scope.

Having shown and described this invention, I claim:

In combination with a combustion chamber having an exhaust opening at one end thereof, a plurality of nozzles projecting through opposite lateral sides of the chamber, means for compressing fresh air, pipes for conducting said compressed air to and injecting it into said nozzles, said pipes and nozzles being arranged for entraining atmospheric air upon the compressed air entering the nozzles, and spray heads on the exhaust ends of the nozzles adapted to deliver the air from the nozzles toward the middle and toward the exhaust end of the chamber in a single continuous thin sheet of air extending over substantially the entire horizontal cross section of said chamber.

In witness of the foregoing I affix my signature.

FRANK W. MILLER.
